D12-18.

OR D 18,830 EX

DESIGN.

H. C. ARMSTRONG.

WAGON BODY.

No. 18,830.

Patented Jan. 1, 1889.

UNITED STATES PATENT OFFICE.

HENRY C. ARMSTRONG, OF PROVIDENCE, RHODE ISLAND.

DESIGN FOR A WAGON-BODY.

SPECIFICATION forming part of Design No. 18,830, dated January 1, 1889.

Application filed September 1, 1888. Serial No. 284,371. Term of patent 14 years.

To all whom it may concern:

Be it known that I, HENRY C. ARMSTRONG, of the city of Providence, county of Providence, and State of Rhode Island, have invented and produced a new and original Design for a Wagon-Body, of which the following is a full, clear, and exact description, reference being had to the accompanying photograph, forming part of this specification.

10 The photograph is a perspective view of my new design for a wagon-body. The leading feature of my design consists in the spherical form of the wagon-body.

15 In the photograph, 1 designates the main body of the wagon; 2, the cab placed in front of the globular wagon-body; 3, the piece connecting the globular or spherical body of the wagon with the cab.

The globe or sphere may be painted any

desired color, or it may be gilded. A map of 20 the world or parts of the world may be painted on the same, as is shown in the photograph. The globe may be ornamented by placing a crown, an eagle, or, as shown in the photograph, by placing the representation of a whale 25 on the summit of the globe or sphere.

Having thus described my new and original design, I claim as new and desire to secure by Letters Patent—

20 The design for the body of a wagon 30 shown and described, the same comprising the globular form of the main body and the cab projecting beyond the globular main body, as set forth.

HENRY C. ARMSTRONG.
